UNITED STATES PATENT OFFICE.

ADOLPH M. HOLSTEIN, OF SYRACUSE, NEW YORK.

DRAWER HANDLE.

Application filed May 3, 1923. Serial No. 636,468.

This invention relates to handles on drawers and the like and has as its object, a particularly simple, efficient and compact construction by which the attaching member as a screw which extends through the front wall of a drawer, can be attached to an ornamental handle or knob of wood, composition or other substances, so that the handle or knob cannot become detached. 5 The invention consists in the novel features and in the combinations and constructions hereinafter set forth and claimed.

In describing this invention, reference being had to the accompanying drawing in 15 which like characters designate corresponding parts in all the views.

Figure 1 is an enlarged sectional view of 20 this drawer handle, the continuous portion of the drawer being also shown.

Figure 2 is a sectional view of the body of the knob or handle.

Figures 3 and 4 are elevations, respectively, of the outer and inner bushings.

Figure 5 is a view similar to Figure 1, 25 parts being omitted showing the outer bushing as split by the inner bushing inward to firmly attach the bushings to the knob or handle.

This drawer handle comprises a body or 30 knob having a recess 2 through its rear face, an outer sleeve or bushing and an inner bushing, the former drive fitting the recess and the latter drive fitting the former, the inner bushing having means for 35 expanding the outer bushing when the bushings are driven into the recess.

1 designates the body or the knob of the handle, and 2 the recess which is preferably 40 cylindrical and which opens through the rear face of the body or knob and has a bottom 3. The knob is preferably wood or wood composition. 4 is the outer sleeve or bushing which is preferably of wood and 5 is the inner bushing which is metal, the outer bushing 4 drive fitting the recess 2 and the inner bushing 3 drive fitting within the sleeve 4 and having means, as an enlargement or head 6 at its inner end which embeds in the inner end of the sleeve 4 when 45 these parts 4 and 5 are driven into the recess 2, and the metal bushing or the head thereof thrust against the bottom 3. The head 6 is preferably non circular and is usually angular, square or hexagonal.

55 The inner bushing 5 is first inserted part way into the sleeve 4 and then the sleeve

4 inserted part way in the recess 2. The body 1 with these parts so arranged is then placed under a press and the parts 4 and 5 driven into the recess 2. When the head 6 engages the bottom of the recess 2, its inward movement is limited and, as the inward movement of the sleeve 4 continues, the head 6 is embedded in the inner end of the sleeve 4, so that the sleeve 4 is split and so snugly fitted into the recess that it is practically integral with the body 1. Usually glue is placed in the recess or on the sleeve before the parts are driven into the recess 2.

The inner bushing 5 is formed with a threaded passage for receiving a screw 7 extending through the front wall 8 of the drawer from the inner side thereof and threading into the threaded passage of the 75 sleeve or bushing 5.

By my invention, handles or knobs can be firmly attached to the drawers of other articles, so that they cannot work loose nor can the knobs become loose from the bushings to which the screw 6 is attached.

What I claim is:

1. A drawer handle comprising a body formed with a recess, a second bushing 85 substantially fitting the recess, a first bushing within the first bushing, the first bushing having a drive fit in the recess throughout the length of the bushing and the second bushing having a drive fit within the first bushing throughout the length of the second 90 bushing, the second bushing having a non-circular head embedded in the first bushing.

2. A drawer handle comprising a wood body having a recess opening through its rear face, a wood bushing and a metal bushing 95 within the wood bushing, the wood bushing drive fitting the recess and the metal bushing drive fitting within the wood bushing having means for splitting the wood bushing when the bushings are located in 100 the recess.

3. A drawer handle comprising a body formed with a cylindrical recess opening through its rear face, a cylindrical bushing and an inner bushing within the former bushing, the first mentioned bushing drive fitting the recess and the inner bushing drive fitting the outer bushing and having a head at its inner end embedded in the outer bushing when the bushings engage 110 the bottom of the recess.

4. A drawer handle comprising a wood

- body having a recess opening through its rear face, a split wood bushing and a metal bushing within the wood bushing, the wood bushing drive fitting the recess and the metal bushing drive fitting within the wood bushing and having a head in its inner end embedded in the wood bushing.
5. A drawer handle comprising a body formed with a cylindrical recess opening through its rear face, a cylindrical bushing and an inner bushing within the former bushing, the first mentioned bushing drive fitting the recess and the inner bushing drive fitting the outer bushing and having an angular head at its inner end embedded in the outer bushing.

6. A drawer handle comprising a wood body having a recess opening through the rear face, a wood bushing and a metal bushing within the wood bushing, the wood bushing drive fitting the recess and the metal bushing drive fitting within the wood bushing having means for splitting the wood bushing when the bushings approach the bottom of the recess, the metal bushing having a threaded passage for receiving an attaching screw. 20 25

In testimony whereof, I have hereunto signed my name, at Syracuse, in the county of Onondaga and State of New York, this 30 30th day of April, 1923.

ADOLPH M. HOLSTEIN.
